UNITED STATES PATENT OFFICE.

LEOPOLD A. HEINE, OF CHICAGO, ILLINOIS.

ELECTRICALLY-OPERATED COIN-CONTROLLED MECHANISM.

1,236,168.

Specification of Letters Patent.

Patented Aug. 7, 1917.

Application filed December 27, 1915. Serial No. 68,670.

To all whom it may concern:

Be it known that I, LEOPOLD A. HEINE, a citizen of the United States, residing at the city of Chicago, in the county of Cook 5 and State of Illinois, have invented certain new and useful Improvements in Electrically-Operated Coin-Controlled Mechanism, of which the following is a specification.

My invention relates to electrical, coin 10 operated prepayment devices of the type adapted to be used in connection with electric motors or motor driven mechanisms. I am aware that coin operated motor meters for various uses, such as supplying a customer with electric current from a central station company's mains have been developed and are in use, also that coin operating fan motors are common, and it is in relation to these devices that my invention 15 is an improvement.

My device is simple in construction and cheap to manufacture, and the same may be readily installed in connection with standard mechanism. Its action is immediate 20 and positive, and the construction is such as to guard against the use of coins of wrong denomination and of disks of metal of improper size for its operation. Furthermore, its action is such as to prevent the insertion 25 of additional coins while the mechanism is in operation, and at the same time such as to allow the mechanism to be stopped and started again by turning the current off and on until the prepaid service has 30 been rendered.

In the drawings:

Figure 1 shows a sectional elevation of my invention in geared relation to a motor whose operation it controls;

40 Fig. 2 is a sectional plan view of the mechanism on the line A—A of Fig. 1;

Fig. 3 is a sectional elevation on the line B—B of Fig. 2, and

45 Fig. 4 is an elevation of the control disk viewed from the reverse direction from that shown in Fig. 1.

Referring to Fig. 1 for a general understanding of the invention, 1 is the motor whose shaft 2 connects by means of the 50 worm 3, the gear 4, and the shaft 5, to the control mechanism inclosed in the case 6. Inside the case 6 the shaft 5 is connected to the rotatable control disk 8 through the worm 9 and the gear 10. The control disk 55 10 is made of insulating material, such as fiber, or some other form of molded insula-

tion, and is provided with a flange 11, which is cut away at a point 12 on its circumference to provide a slot into which a coin 13 can be dropped when it registers with the 60 slot 14 in the case. Fastened to the back of the disk and concentric with it there is a contact ring 15 of brass or other conducting material, which forms a part of the motor circuit via the brushes 16 and 17, 65 the brush holders 18 and 19, and the leading in wires 20 and 21. (See Figs. 2 and 3).

At 22 the contact ring 15 has a circular hole cut through it of such diameter as to be slightly larger than the diameter of the 70 brushes 16 and 17. In the center of this hole a contact pin or lug 23 is mounted so as to come flush with the contact ring face on the one side and to project through the insulating disk some distance on the other 75 side to provide a rest or stop for the coin to rest on when the disk is in proper position. At 24 a second contact pin or lug passes through the control disk which also 80 serves as a rest or stop for the coin. Pin 24 is secured to the contact ring 15 and is in electrical contact with it. 25 is a coin receptacle.

The operation of the device hence is as follows: When a coin of proper size is 85 dropped onto the pins 23 and 24 connection is made completing the motor circuit so that the current enters, say terminal 21, passes through the brush holder 19, the brush 17, to the pin 24, thence through the coin to 90 pin 23, and out through brush 16 to terminal 20. The motor consequently starts and the disk begins to move at a definite rate proportional thereto dependent on the gear train ratio. As it does so the brush 16 begins 95 to bear on the contact ring 15 as well as on the pin 23, hence making a more direct path for the current from terminal 21 to terminal 20, namely, through brush 17, the contact ring 15, thence through brush 16 to terminal 20. A moment later the disk has rotated so that the coin is out of the circuit altogether. The slot in the disk is hence out of register with the slot in the case, and no 100 coin can now be inserted until the disk is again in its position under the slot in the case. The stopping of the motor at the end of the prepaid period occurs in the following manner: Since the gear ratio is so fixed that one complete revolution of the disk 105 corresponds to the prepaid service in amount, the circuit is to be opened when 110

the revolution of the contact disk is completed. This is accomplished automatically, due to the falling of the coin from its position on the pins to the receptacle 5 below after the disk has made approximately a quarter turn. As a result when the hole 22 in the contact ring 15 again assumes a position so that brush 16 bears only on pin 23 at its center and not on the contact 10 ring the circuit is open and can only be re-established by the insertion of another coin.

It is readily seen that coins of smaller diameter than proper would fall into the coin box at once and not start the motor. Likewise that the disk is chamfered at the flange 15 to prevent coins from finding a resting place on their way to the coin receptacle.

I claim:

1. In a coin controlled device, the combination with an electric current and the mechanism driven thereby, of a rotating disk of insulating material actuated by the mechanism at a speed proportional to the speed of said mechanism, a contact ring 20 mounted on the said disk, a plurality of brushes in the circuit spaced from each other and adapted to bear on said ring, an electrically conductive lug on said disk extended to the bearing face of the contact 25 ring but insulated therefrom, and a second electrically conductive lug on said disk connected to said contact ring, said lugs being spaced from each other by less than the diameter of the controlling coin.

2. In a coin controlled device, the combination with an electric current and the mechanism driven thereby, of a rotating disk of insulating material actuated by the mechanism at a speed proportional to the speed of said mechanism, a contact ring 40 mounted on the said disk, a plurality of brushes in the circuit spaced from each other and adapted to bear on said ring at different radial distances from the center 45 thereof, an electrically conductive lug on said disk extended to the bearing face of the contact ring but insulated therefrom, and a second electrically conductive lug on said disk connected to said contact ring, 50 said lugs being spaced from each other by less than the diameter of the controlling coin.

3. In a coin controlled device having a casting provided with a coin inlet opening, a disk having a continuous body portion rotatable by the driven mechanism, a laterally extended annular flange on the face of the disk adjacent to its periphery having a notch 55 registerable with the said inlet opening, and a device on the disk within the said flange adapted to support the coin until the said notch is out of register with said coin opening.

4. In a coin controlled device having a 60 casting provided with a coin inlet opening,

a disk having a continuous body portion rotatable by the driven mechanism spaced from the casing by a distance less than the thickness of the controlling coin, a laterally extended annular flange on the face of the disk 70 adjacent to its periphery chamfered on its inner face and having a notch registerable with the said inlet opening, and a device on the disk within the said flange adapted to support the coin until the said notch is out 75 of register with said coin opening.

5. In an electrically operated coin controlled device, the combination of a motor, an insulating control disk driven by the motor, a contact ring on one face of said 80 disk, a conducting lug set into said ring but insulated therefrom, brushes bearing on said ring, contact extensions or pins projecting from the other face of said ring and said lug adapted to receive a coin whereby a circuit 85 is closed and a cycle of operations results.

6. In an electrically operated coin controlled device, the combination of a motor, an insulating control disk driven by the 90 motor, a contact ring on one face of said disk, a conducting lug set into said ring but insulated therefrom, brushes bearing on said ring, contact extensions or pins projecting from the other face of said ring and said 95 lug adapted to receive a coin whereby a circuit traverses the coin until the mechanism has moved to establish a circuit through the contact ring.

7. In an electrically operated coin controlled device; the combination with a motor of a contact ring adapted to form a part of the motor circuit and driven by the motor, a brush normally out of contact with said ring and forming a part of the motor circuit, coin closable means for establishing the electrical connection of the said brush and the said ring, and means for breaking the connection thereof at a predetermined point of operation.

8. In an electrically operated coin controlled device; the combination with a motor of a plurality of brushes in the motor circuit, a contact ring driven by the motor providing a continuous bearing path for one of said 115 brushes and cut away to provide a discontinuous bearing path for the other of said brushes, a contact piece in the cutaway portion of the contact ring and insulated therefrom, and means for receiving a coin to form 120 an electric connection between said contact piece and said contact ring.

9. In an electrically operated coin controlled device; the combination with a motor of a contact ring in the motor circuit driven 125 by the motor and having a discontinuous portion, a brush in the motor circuit having a bearing path on the contact ring including said discontinuous portion, a contact piece in said discontinuous section insulated from 130

- the contact ring, and means for receiving a coin to form an electric connection between said contact piece and said contact ring.
10. In an electrically operated coin controlled device; the combination with a motor of a contact ring adapted to form a part of the motor circuit driven by the motor and having a discontinuous portion, a brush in the motor circuit having a bearing path
- 5 on the contact ring including said discontinuous portion, a contact piece in said discontinuous section insulated from the con-
- tact ring, and means for receiving a coin to form an electric connection between said contact piece and said contact ring. 15
- In witness whereof, I have hereunto subscribed my name, this 24th day of December 1915, in the presence of two subscribing witnesses.

LEOPOLD A. HEINE.
